US00D998718S

(12) **United States Design Patent** (10) **Patent No.:** **US D998,718 S**
(45) **Date of Patent:** **** Sep. 12, 2023**

(54) **GYROSCOPE TOY**

(71) Applicant: **Shenzhen Kean Silicone Product Co., Ltd.**, Shenzhen (CN)

(72) Inventor: **Pandian Peng**, Shenzhen (CN)

(**) Term: **15 Years**

(21) Appl. No.: **35/514,951**

(22) Filed: **Jul. 26, 2022**

(80) **Hague Agreement Data**

Int. Filing Date: **Jul. 26, 2022**

Int. Reg. No.: **DM/222619**

Int. Reg. Date: **Jul. 26, 2022**

Int. Reg. Pub. Date: **Aug. 12, 2022**

(30) **Foreign Application Priority Data**

Feb. 25, 2022 (CN) 202230091618.9
